UNITED STATES PATENT OFFICE

105,849

DESIGN FOR A COMBINED SHREDDER, SLICER, AND PEELER

Melvin B. Dutrow, Evansville, Ind., and Walter
J. Mitchell, Chicago, Ill.

Application February 23, 1937, Serial No. 67,808

Term of patent 7 years

To all whom it may concern:

Be it known that we, Melvin B. Dutrow and Walter J. Mitchell, citizens of the United States and residents of Evansville, Vanderburgh County, Indiana, and Chicago, Cook County, Illinois, respectively, have invented a new, original, and ornamental Design for a Combined Shredder, Slicer, and Peeler, of which the following is a specification, reference being had to the accompanying drawing, forming part thereof.

In the drawing, Fig. 1 is a front elevational view of a combined shredder, slicer and peeler embodying our new design;

Fig. 2 is a top plan view; and

Fig. 3 is a side elevational view thereof.

We claim:

The ornamental design for a combined shredder, slicer, and peeler as shown.

MELVIN B. DUTROW.

WALTER J. MITCHELL.
